His Attorney.

UNITED STATES PATENT OFFICE

ALBERT NARATH, OF BERLIN, GERMANY, ASSIGNOR TO GENERAL ELECTRIC COMPANY,
A CORPORATION OF NEW YORK

SOUND RECORDING AND REPRODUCING

Application filed January 30, 1930, Serial No. 424,696, and in Germany February 12, 1929.

My invention relates to the photographic recording and reproducing of sound. In reproducing from film sound records it is sometimes desirable, in order to obtain special effects, to have various sounds or sound events, which may be widely different in character, follow each other and in so following to gradually blend or merge the one into the other. These sound events may have been originally recorded at various times and places and without regard to their being reproduced in the manner mentioned.

It is one object of my invention to provide an improved method of making a photographic record of a plurality of sound events which when reproduced shall merge the one into the next. Another object of my invention is the provision of the improved record resulting from that method.

My invention will be better understood from the following description taken in connection with the accompanying drawings, and its scope will be pointed out in the appended claims.

Referring to the drawings, Fig. 1 is a diagrammatic view of apparatus by means of which the method forming a part of my invention may be carried out, and Fig. 2 shows a portion of the film made in accordance with that method.

In Fig. 1, which shows by way of example apparatus for making a variable intensity sound record by the use of a Kerr cell, light rays from the light source 1 pass through the condensing lens 2 and the Kerr cell 3 and finally impinge on the moving light-sensitive film 4, suitable means, examples of which are well known, being employed to limit the width of the line of light directed on the film. In the well-known manner as shown for example in the British Karolus Patent 235,857, the Kerr cell may be connected through suitable amplifying devices to a sound pick-up device or, if a r-r-recording is being made from a previously made sound record, the Kerr cell may be connected through suitable amplifying devices with the output circuit of a reproducer of the original record. When in the recording process that point on the film 4 is reached at which it is

desired that the sound event then being recorded shall begin to fade away and another sound event rise in its stead the amount of light reaching the film is gradually diminished. This may be accomplished in various ways; for example as shown in the Ries Patent 1,473,976, by decreasing the brilliancy of the source 1, which if an electric lamp may have its current reduced or by inserting various devices in the path of the rays such as diaphragms or light absorbing screens. I prefer, however, to interpose in the path of the rays the diaphragm 5 having an opening therein for the rays such that when the diaphragm is moved the width of light beam directed on the film being exposed is varied between a maximum and a minimum. As the diaphragm is thus moved, the record 6 of the first sound event is gradually reduced in width from the full width of the sound track to zero. The film is then stopped and moved back to the point at which the reduction in width of the sound track began. The film is again moved forward while the next sound event is recorded, the diaphragm being now positioned to allow the light to fall on the unexposed portion of the film beginning with a zero width and gradually moving the diaphragm to expose the full width of the sound track, thus forming the record 7 of the second sound even. As shown in Fig. 2 these two records 6 and 7 have tapering portions which overlap each other. When sound reproduction is made from a film such as shown in Fig. 2, the two sound events blend or merge the one into the other, the time required for the merging being dependent upon the length of the overlapping tapered portions.

While this method may be used for the original recording of the sound events it is particularly applicable for use when copying on a single film sound events originally recorded on separate films but which when reproduced from the copy shall merge the one into the other. The copying may be done in various well known ways such as by contact or optical printers with which the amount of light reaching the film is varied as described when that part of the film is 10.

reached at which the merging of the sound events is to take place or the copying may be done by re-recording the separate sound events on the single film by the use in the manner described of apparatus such as shown in Fig. 1.

What I claim as new and desire to secure by Letters Patent of the United States is:—

1. The method of photographically recording on a single light-sensitive member a plurality of different sound events so as to merge one into another upon reproduction which comprises gradually reducing the exposing light while one sound event is being recorded on a certain length of the member and increasing gradually the exposing light while another sound event is being recorded on the same length of the member.

2. The method of photographically recording on a single light-sensitive member a plurality of different sound events so as to merge into one another upon reproduction, of which events separate records previously have been made, which comprises gradually reducing the exposing light while the vibrations corresponding to one record are being recorded on a certain length of the member and gradually increasing the exposing light while the vibrations corresponding to another record are being recorded on the same length of the member.

3. The method of copying on the same length of film sound records of a plurality of different sound events so that they shall merge one into another upon reproduction which comprises exposing said film length to light varied in accordance with one of said records while simultaneously decreasing the amount of light reaching the film, and exposing said length to light varied in accordance with another of said records while simultaneously increasing the amount of light reaching the film.

4. The method of re-recording on the same length of film two different sound records previously recorded on separate films such that upon reproduction the recorded sounds shall merge the one into the other which method comprises exposing said length of film to light varied in accordance with one of said records while steadily decreasing the width of the film being exposed, and exposing the same length of film to light varied in accordance with another of said records while steadily increasing the width of the film being exposed.

5. A sound record film having thereon a plurality of successive variable intensity records of different sound events adapted upon reproduction to merge the one into the next one following, the adjacent ends of said records being tapered and the tapered portions arranged to overlap each other.

6. A sound record film having thereon a plurality of successive variable intensity rec-

ords of different sound events adapted upon reproduction to merge the one into the next one following, said records having wedge-shaped overlapping adjacent end portions.

In witness whereof, I have hereunto set my hand this 6th day of January, 1930.

ALBERT NARATH.
